UNITED STATES PATENT OFFICE

EUGENE C. GWALTNEY, OF LAURINBURG, NORTH CAROLINA

COTTON-CLEANING MACHINE

Application filed July 9, 1927, Serial No. 204,541. Renewed October 24, 1929.

My invention relates to an improvement in cotton cleaning machine.

In all preparatory cleaning machines now in use in the cotton manufacturing trade through which material passes before carding, the picker, which is usually a beater composed of two or more revolving knives, or a cylinder covered with pins (or what is known as a "porcupine beater"), has either been placed horizontally or vertically to the length of the machine, the cotton passing entirely through one picker at a time, all cotton passing through the same element. This, to insure large production and low operating cost, has placed a tremendous capacity on the picker, greater in fact than the element can properly handle, resulting in the cleaning of cotton up to the card being done by detaching tufts or bunches of fibres rather than the individual fibres or very small masses. It is well known that the more finely the cotton fibres are subdivided in the process of cleaning, the cleaner the resultant cotton will be with less damage to fibres.

My new cleaning machine contemplates a plurality of pickers to a condenser. The work of each picker is reduced in proportion to the number of the elements applied to each condenser, all of the cotton not passing through each element but only the proportionate part of the cotton to the number of elements. For instance, a four picker machine will handle only one-fourth of the total amount of cotton handled in this machine. By reducing the amount of work to be done by each picker, use can be made of the cleaning and parallelization action of the feed-plate and licker-in, which has hitherto only been applied to cards and low grade cotton cleaning machines of very low production as in the latter machines the licker-ins are set in series and not in parallel. The pickers in my new machine may be set either with the axis at right-angles to the screens and lap-forming attachment, or may be set at an angle other than parallel, the opposite elements farthest from the machine may be placed very closely together, resulting in a modified V-shape, the open end of the V delivering to the screen element of the picker.

In this new process of cotton manufacture, the use of cards, which has heretofore been regarded as necessary in the manufacture of cotton and other fibrous materials, may be entirely eliminated in the manufacture of 53 combed yarns.

In my present invention, I secure a cleaner cotton, more evenly divided, with less waste of good fibre, due to the use of a plurality of pickers over a single one as hitherto used, to a condenser, so that I obtain what might be termed individual fibre cleaning as compared with mass-cleaning as heretofore practiced.

This machine consists of a lap-forming section which contains a screen section to form a sheet of cotton by air suction which is delivered to a calendar roll section, compresses the sheet and winds the same in the form of a lap of the proper width, density, and weight, to be put up at the ribbon lap machine to prepare laps for combing or carding in connection with pickers to consist of two or more licker-in cylinders similar to those used on revolving flat cards, with feed-plate and feed roller, the cleaning elements 63 being placed other than horizontally or vertically, to the screen or calendar rolls.

The cotton delivered from the licker-in is more nearly straightened and parallelized, due to the combing action of the licker-in than the cotton received from the card, due to the fact that it is impossible for the wire on the card cylinders and flats to hold a fibre and carry it forward without the fibre being doubled back in more or less the form of a 65 loop or closed V, the card action in no wise resembling that of combing, as in combing one end of a fibre must be firmly held while the needles or teeth of the combing device are passed through the mass of fibres. This action is only obtained on the licker-in by the feed-roller holding the mass of fibres and the licker-in teeth passing through the same as they are gradually fed forward until the fibre is finally released from the feed roller.

This action is also present in the comber by reason of the fibres being held by the nippers while the needles of the comber cylinder pass through the mass of fibres so held. In the carding of fibres between two revolving 100

cylinders, or a cylinder and stationary flat, or a flat moving so slightly in relation to the cylinder speed that, in effect, it is stationary, the action does not tend to parallelize the fibres, but rather to double the fibres back around that part of the card wire which is carrying the fibre forward or holding it back. By my present machine and method of preparing the cotton for the combing processes by the use of the licker-in and feed-plate and the combing action attendant thereon while not delivering the fibre to the screen which forms the lap, by air-suction, in a perfectly parallel condition, does avoid the tendency of the card teeth to double up and nip the fibre, and presents the lap for combing in a very much more favorable condition for the action of the combing-needles than one that is carded.

20 The percentage of waste on the latest known combers can be controlled with the use of my machine to such a point that the total waste of a well-combed yarn is very little, if any, greater than the waste made on 25 the present carding systems, the combed yarn being vastly superior to the carded in strength, cleanliness, lustre, and general appearance.

20 The accompanying drawings are diagrammatic views in which:—

Fig. 1 represents a plan view showing a condenser and four pickers from which the cotton is supplied to the condenser;

25 Fig. 2 is a section on the line 2—2 of Fig. 1; and

Fig. 3 is a section on the line 3—3 of Fig. 1.

30 A, represents a condenser of typical form having screen, rollers, fan and the usual elements considered essential to such a device; and B, indicates a plurality of pickers, as, for instance, licker-ins. These fit into common V-shaped channel C, so that the fibres are supplied to the screens from a plurality of pickers B instead of from a single one as heretofore, with the advantageous results that 45 have been fully explained in the preceding part of the specification.

Of course it is understood that four, six, or eight, or in fact any number of these pickers might be used in connection with a single condenser with this arrangement.

I claim:

1. The combination of a condenser and a picker arranged at an angle to the longitudinal axis through the condenser other than a right-angle and in communication with the condenser.

2. The combination of a condenser, a V-shaped channel communicating therewith, and a plurality of pickers at the sides of the channel and communicating therewith.

3. In a machine of the character described, the combination of a cleaning element, a feed channel for delivering cotton fibers to said cleaning element, and a plurality of

pickers arranged approximately on opposite sides of said channel and having the axes thereof disposed at acute angles relative to each other.

4. In a machine of the character described, the combination of a cleaning unit, a feed channel of V-shape disposed in front of said cleaning unit for directing cotton fibers thereto, and a plurality of pickers disposed approximately in the same horizontal plane on opposite sides of said channel for delivering the cotton fibers thereto, said pickers having the axes thereof at acute angles to each other, and at angles to the cleaning unit other than right angles.

5. The combination of a cotton condenser and a plurality of pickers having the axes thereof arranged at acute angles to the axis of the condenser and from which fibers are fed to the condenser.

6. The combination of a condenser, and pickers having the axes thereof arranged other than in parallel relation with the axis of the condenser.

7. The combination of a condenser, a channel leading thereto, and a plurality of pickers arranged on opposite sides of said channel and in communication therewith, said pickers being approximately in the same horizontal plane as the channel.

In testimony whereof I affix my signature.

EUGENE C. GWALTNEY.
